UNITED STATES PATENT OFFICE.

WILLIAM C. YUTZY AND BERTRAM E. HYET, OF CADILLAC, MICHIGAN.

HAT AND COAT RACK.

No. 827,280.

Specification of Letters Patent.

Patented July 31, 1906.

Application filed February 17, 1906. Serial No. 301,643.

To all whom it may concern:

Be it known that we, WILLIAM C. YUTZY and BERTRAM E. HYET, citizens of the United States, residing at Cadillac, in the county of Wexford and State of Michigan, have invented a new and useful Hat and Parcel Rack, of which the following is a specification.

This invention relates to racks for holding hats, parcels, and the like; and its object is to provide a rack the compartments of which are adapted to be closed by means of a curtain which may be utilized for advertising purposes.

Another object is to provide a rack of peculiar construction whereby the curtain will be held in closed position, so as to prevent the removal of the contents of the compartment by unauthorized persons.

With the above and other objects in view the invention consists of a rack containing one or more compartments, and in each compartment is hung a curtain which is fastened at its lower end to a spring-controlled roller mounted on a frame which is slidably mounted between the sides of the compartment. A disk is rotatably mounted within the path of the frame and is adapted to engage and hold said frame, a lock being provided for securing the disk against rotation while the same is in engagement with the frame.

The invention also consists of certain other novel features of construction and combination of parts, which will be hereinafter more fully described, and pointed out in the claims.

In the accompanying drawings we have shown the preferred form of our invention.

In said drawings, Figure 1 is a front perspective of a portion of a rack, one compartment thereof having its closure in lowered position. Fig. 2 is a front elevation of the sliding frame of the closure and the roller thereon, a portion of the roller being shown in section. Fig. 3 is a section through the frame and a portion of the rack and showing the lock in elevation. Fig. 4 is a perspective view of the lock detached and with the disk removed therefrom.

Referring to the figures by numerals of reference, 1 are the sides, and 2 and 3 are the top and bottom, respectively, of the front frame of one of the compartments of a rack 4. This rack may be of any suitable construction, and any desired number of compartments may be employed, and all of its compartments may be of different sizes. The

side strips 1 of each compartment are provided in their inner or adjoining faces with longitudinally-extending grooves 5, and slidably mounted within the grooves of each compartment is a substantially rectangular frame 6, the lower rail of which has its central portion 7 outwardly inclined, so as to project beyond the front of the compartment and constitute a grip. Rotatably mounted on the upper rail of the frame 6 is a roller 8, and a spring 9 is coiled about this rail and within the roller. This spring is secured at opposite ends to the rail and roller, respectively. The curtain 10 is permanently secured along one edge to the top 2 of the front frame of the compartment, while its opposite edge is fastened to the roller 8. When the frame 6 and the roller 8 are in position adjacent the top of their compartment, the curtain is wound about the roller, and the spring 9 is so disposed that when the frame is slid downwardly within the grooves 5 the curtain will unwind from the roller and cause the spring to tension.

A lock 11 is secured within one of the sides 1 of the front frame of the compartment and has a locking-pin 12 normally projected therefrom and adapted to be retracted by means of a suitable key 13. This locking-pin is overlapped by a rotatable disk 14, mounted on a stud 15, which extends from a base-plate 16, fastened to the side strip 1 adjacent the lock 11. The disk has an opening 17 therein adapted to register with the locking-pin, and a notch 18 is formed within the periphery of the disk. This notch is so disposed as to move into register with the groove in the side strip 1, and when in such position the opening 17 registers with the locking-pin 12. The movement of disk 14 is limited by means of a stop-pin 19, which extends from the base-plate 16 into an elongated recess 20, formed in the periphery of the disk. The curtain 10 may have any suitable advertising matter displayed thereon and which will be disclosed whenever the curtain is lowered.

It will of course be understood that the normal position of the frame 6 is close to the top strip 2 of the compartment, and when the frame is in this position the notch 18 in disk 14 is in such position that the frame upon being slid downwardly within the grooves 5 will enter the notch and cause the disk to rotate. This rotation of the disk will continue until the opening 17 registers with the locking-pin 12, whereupon said pin will spring outwardly

into the recess and lock the disk against rotation. The frame 6 will therefore be secured in lowered position, and it is impossible to raise it and obtain access to the interior of the compartment except by first inserting the key 13, so as to retract the locking-pin from engagement with the disk. As the spring 9 is tensioned when the curtain and frame are lowered, it will of course be understood that said spring will promptly wind the curtain upon the roller as soon as the frame is released, and therefore the frame will be slid upward within the grooves 5 to its normal position.

Having thus described the invention, what is claimed is—

1. The combination with a structure having a compartment therein; of a frame slidably mounted between the sides of the compartment, a curtain, means carried by the frame for winding the curtain, a rotatable frame-engaging device mounted upon the structure and a lock for securing said device in engagement with the frame.

2. The combination with a structure containing a compartment; of a frame slidably mounted between the sides of the compartment, a spring-controlled roller carried by the frame, a curtain secured at opposite ends to the structure and roller respectively, a frame-engaging device movably mounted upon the structure and means for locking said device in engagement with the frame.

3. The combination of a structure containing a compartment having grooved sides; of a frame slidably mounted within the grooves, a spring-controlled roller carried by the frame, a curtain secured to the structure and roller, a rotatable frame-engaging device mounted upon the structure and a lock for automatically securing said device in engagement with the frame.

4. The combination of a structure containing a compartment; of a frame slidably

mounted within the compartment, a curtain connected at opposite ends to the structure and frame respectively, a notched disk rotatably mounted upon the structure, said notch adapted to receive a portion of the frame, and means for locking the disk when in engagement with the frame.

5. The combination with a structure containing a compartment; of a frame slidably mounted within the compartment, a curtain connected at opposite ends to the structure and frame respectively, a notched and apertured disk rotatably mounted upon the structure, said notch adapted to receive a portion of the frame, and a locking-pin adapted to be automatically seated within the aperture in the disk to lock said disk in engagement with the frame.

6. The combination with a structure; of a frame slidably mounted within said structure, a curtain connected at its ends to the structure and frame respectively, a disk rotatably mounted in the structure and having a frame-receiving notch in the periphery thereof, and means for automatically locking the disk when in engagement with the frame.

7. The combination with a suitable structure, of a frame slidably mounted therein, a spring-controlled roller carried by the frame, a curtain secured at its ends to the structure and roller respectively, a disk rotatably mounted upon the structure and having a frame-receiving notch in its periphery, and means for automatically engaging the disk to lock the same in engagement with the frame.

In testimony that we claim the foregoing as our own we have hereto affixed our signatures in the presence of two witnesses.

WILLIAM C. YUTZY.
BERTRAM E. HYET.
